UNITED STATES PATENT OFFICE

DELBERT ELLIS, OF TURTLE CREEK, PENNSYLVANIA, ASSIGNOR TO WESTINGHOUSE ELECTRIC & MANUFACTURING COMPANY, A CORPORATION OF PENNSYLVANIA

ARC BOX

Application filed September 23, 1927. Serial No. 221,417.

My invention relates to electrical contactors and particularly to arc-extinguishing devices therefor.

One object of my invention is to provide means to extinguish the arc incident to the opening of the separable contacts of a circuit interrupter without the use of a blow-out magnet such as is usual in the prior art, where contacts opening in air are employed.

10 Another object of my invention is to provide a structure which will prevent the gases and particles of molten metal, which are evolved when a pair of separable contacts opens in air while carrying current, from flying into the space surrounding the contactor.

20 A further object of my invention is to provide a unitary structure for extinguishing the arcs incident to the opening of the contact members of a circuit interrupter that shall be relatively cheap and simple to manufacture.

Other objects of my invention will become apparent upon reading the following specification taken in connection with the drawing, wherein:

25 Figure 1 shows a view in elevation from the front side of a contactor embodying my invention, and

30 Fig. 2 shows a sectional view taken along the line II-II, in Fig. 1.

In circuit interrupters and contactors of the prior art in which the circuit is to be opened under load by contacts opening in air, 35 it has been customary to provide a blow-out magnet which would set up a sufficiently powerful magnetic field transverse to the arc which is drawn when the contacts open to deflect it rapidly upward and blow it out.

40 Such blowout magnets are relatively expensive components of circuit interrupters and it is desirable, in the case of contactors employed for moderate voltages and currents, such for example as for service in induction motor starters, to avoid the necessity for providing such magnets.

45 In accordance with my invention I employ, instead of the typical blow-out magnet of the prior art, a structure in which the arcs 50 are extinguished within a chamber which has

openings at the top. The upward draft of the hot gases, confined within such a chamber, exerts a force which brings about the rapid extinction of the arc. In order to prevent hot arc gases and molten particles 55 of metal from being projected from the top of this chimney like structure, I provide a partition transverse thereto near the top, comprising a metal screen.

While the arc extinguishing device which 60 I have invented may be used on direct-current circuits, it is particularly effective on alternating current circuits, owing to the fact that when the current passes through zero in the course of the alternating current cycle, the 65 ionization of the arc path is rapidly destroyed because of the proximity of the walls of the chamber. The metal screen also has a powerful effect in destroying ionization. The 70 resistance of the arc path is thereby caused to rise to such a value that current flow ceases and the arc remains extinguished.

Referring to the drawing in detail, a contactor embodying my invention comprises a base panel 1 which may be of any suitable 75 insulating material well known in the art, upon which are mounted stationary contacts 2, with which movable contacts 3 cooperate. The contacts 3 are supported on arms 4 having projections 5, containing rectangular 80 slots through which the members 3 may be inserted. Springs 6 bear against one end of these slots and retain the members 3 in position therein. The lower ends of the members 3 are connected by flexible leads 7 85 to terminals 8 mounted on the panel 1. The arms 4 are securely fixed to a cross bar 9, which is supported on trunnions 10, which seat in brackets 11 mounted on the panel 1.

The contacts 3 are opened and closed by 90 the attraction of a holding magnet 13, which is mounted on the panel 1, and which attracts an armature 14 to which the cross-bar 9 is affixed. The magnet may be connected across a phase by connecting one end 95 of its winding to a member 2 and the other end of the winding through a control switch to another contact member 2. The opening and closing of contacts 2 and 3 may then be controlled by said switch. 100

The foregoing construction should be clear to persons familiar with the circuit breaker and the contactor arts.

The line conductors may be connected to terminals 16 which connect directly with stationary contacts 2 and the load conductors may be connected to terminals 8 already described. Fig. 1 shows a contactor adapted for a supply circuit having three wires, but it obviously may be readily modified to adapt it for any number of line conductors.

The arc extinguishing device which is provided in accordance with my invention, comprises a set of deionizing chambers 21 rising vertically above each pair of separable contacts. These may readily be constructed by providing a box like structure of suitable refractory insulating material such, for example, as asbestos board having a front wall 22, a rear wall 23, and two side walls 24. This structure may conveniently be divided into separate chambers for each pair of separable contacts by partitions 25 extending between the front wall 22 and rear wall 23. The rear wall 23 is provided with indentations which permit it to slip over the stationary contacts 2. It may be supported by pushing it down between the contact 2 and a projecting horn 26 attached thereto. The upper end of this deionizing structure is provided with a cover 27, which clamps down upon the top of the walls thereof a screen 28 which may, for example, be of copper gauze, of 16 mesh and comprising wires .03 inches in diameter. The cover member 27 may be held securely in place by bolts 29 which pass through the side walls 24.

Such being the preferred structure of a contactor embodying my invention, the operation thereof will be readily apparent. When the contacts 2 and 3 open under load, the arc thereof heats the air within the chambers 21 and causes a rapid upward draft thereof. This causes the arc to rapidly elongate and fill the upper portion of the chamber. Contact of the arc gases with the refractory walls rapidly deionizes them, even when the current flow continues. When, during the course of an alternating current wave, the current sinks to zero, the deionizing action is extremely rapid and the arc path so rapidly loses its conductivity that the arc remains extinguished.

Any portion of ionized gas which comes in contact with the screen 28 is rapidly deprived of conductivity thereby.

It will, therefore, be evident that I have provided a contactor with means for rapidly extinguishing the arc without the necessity of employing a separate blowout magnet. The structure which I have described is simple and may be cheaply constructed out of materials which are standard in the arts.

While I have described one embodiment of my invention, it will be readily apparent to persons of skill in the art that the principles thereof may be embodied in structures different from that which I have utilized. I therefore desire that the appended claim shall be given the broadest interpretation of which its terms are susceptible in view of the prior art.

I claim as my invention:

A circuit interrupter including a pair of separable contacts mounted within an arc-quenching chamber, said chamber being open at the top and bottom and having side walls of refractory insulating material, the walls of said chamber being in two sections and having a wire screen secured between said two sections across the opening at the top of the chamber.

In testimony whereof, I have hereunto subscribed my name this 19th day of September, 1927.

DELBERT ELLIS.
